UNITED STATES PATENT OFFICE.

MICHAEL LIPTAK, OF ST. PAUL, MINNESOTA.

FIRE WALL.

Application filed October 11, 1926. Serial No. 140,888.

This invention relates to improvements in fire walls and is particularly directed to a construction for reinforcing the walls to prevent bulging and cracking, this reinforcement being in the nature of metallic elements arranged in and forming an outer portion of the permanent wall.

An object of the invention is to arrange metallic horizontal anchoring and stiffening elements at levels between or at the same level as those elements of an adjacent wall side; to anchor and secure certain shelf-forming fire brick header elements upon the metallic elements, against longitudinal movement; to provide a metallic reinforcing structure for and as a part of the permanent wall, and including horizontal reinforcing and tie elements of metal; to provide a structure, the horizontal elements of which can be arranged at any level conformably to the level of the masonry courses to secure certain shelf-forming fire-brick header elements to the reinforcing and tie elements; to provide means whereby the shelf-forming header elements can be secured to the tie elements against longitudinal movement, even when said header elements lie at a level above the metallic stiffening and tie elements; to arrange the metallic stiffener elements in the outer portion of the wall; to protect the metallic structure and form an outer permanent wall thereon, by the use of courses of common bricks extending between the headers and their metallic reinforcing elements; to protect the inner surfaces of the common brick and metallic elements by courses of fire brick laid as stretchers as part of the permanent wall; to provide a replaceable wall supported by shelf-forming headers and comprising fire bricks laid as headers and projecting beyond the inner ends of the supporting headers; to provide additional fire brick laid as stretchers between the fire brick headers; to protect the inner ends of the shelf-forming headers; and to provide a shelf-forming header element as an article of manufacture, adapted for attachment, even though arranged at a level above, a metallic reinforcing element.

Features of the invention include the details of construction of the reinforcing means per se, as well as the construction of the permanent wall carried by the reinforcing means; the provision of relatively thick elongated fire brick header elements project-

ing at the inner side of and forming a part of the permanent wall to form shelves; the arrangement of replaceable fire bricks in header formation between consecutive shelf-forming elements; the arrangement of fire brick as stretchers for protecting the inner ends of the shelf-forming headers; the provision of a header unit, adapted to be secured against movement in a longitudinal direction, and the provision of such an element having corner notches.

Other objects, advantages and features of the invention will be set forth in the description of the drawings forming part of this application and in said drawings,

Figure 1 is a perspective view of the fire wall constructed in accordance with the teachings of this invention, certain of the bricks being removed to more clearly illustrate its construction;

Figure 2 is a perspective view, with the upper portion of the wall entirely removed to more clearly show the construction and arrangement of the adjustable reinforcing elements;

Figure 3 is a plan section showing the complete set-up of the reinforcing frame;

Figure 4 is a detail cross-section through the finished wall;

Figure 5 is a detail view of the structure for obtaining vertical adjustment of the metallic reinforcing elements;

Figure 6 is a perspective view of one of the fire brick header, tie, and shelf-forming elements.

Figure 7 is a vertical section showing the metallic horizontal reinforcing elements, of adjacent sides, in the same plane, with bolts used as securing means.

Figure 8 is a plan section showing the metallic horizontal reinforcing elements, of adjacent sides, in the same plane, and held by bolts, the bolt receiving openings in the corner irons being drilled on the job; and

Figure 9 is a vertical section on the line 9—9 of Figure 8.

In building the wall I primarily set up a structural iron frame comprising corner posts 1, as angle irons, at one end, and corner posts 2 as angle or channel irons at the opposite end. These irons are ordinarily related as the corners of a rectangle (see Figure 3). Lengthwise between the post-forming irons, on three sides, I arrange a series of superposed irons 4 shown as channel irons,

which are connected at opposite ends to the posts after proper vertical adjustment, to conform to the levels of the masonry courses. The channel irons, as combined buck-stays 5 and tie elements, are laid with their concave sides facing upwardly. The stay and tie irons are disposed at the outer side of and form a part of the permanent wall. A means used for adjustably attaching the reinforcing members is best shown in Figure 5, and comprises an angle iron or bracket 10 riveted as at 11 terminally to the upper side of the element, and having a slot 12 in its opposite arm through which a bolt 13 projects as shown, the bolt non-adjustably traversing one of the flanges of the post-forming irons. It will be noted by reference to Figure 2 that with this construction the stiffening elements of one wall lie at levels between 15 those of an adjacent wall.

A staggered relation may thus be produced which provides the more efficient stiffening construction. However, I do not limit myself to the use of the bracket 10, but as shown in Figures 7, 8 and 9 propose to secure the metallic elements by means of bolts 19, the openings for the bolts in the corner irons being drilled on the job.

A plate 15, see Figure 3, may close one end 30 of the frame structure as shown in Figure 3, and the plate is suitably clamped to the channel irons by brackets or hooklike fastening devices 16.

In some instances, the brackets 10 may be dispensed with and the ends of the channel irons 4 mitered as shown at 17 in Figure 8, in which the irons are arranged in the same plane, see also Figure 9. The openings 18 of the corner posts 1 are in this instance bored on the job, and at the proper height as determined by the level of the underlying brick courses. Bolts 19 traverse all irons as shown. Figure 7 shows the structure of the finished wall with the horizontal reinforcing channels in the same plane. Figures 7, 8 and 9 show corresponding constructions.

It will be understood that the irons 4 can be arranged at any level, and that the corner posts can all be of angle iron material. The irons 4 of adjacent sides can be arranged at the same or at different levels. It will be further noted that in some instances the channels 4 may be connected by their ends between and to boiler or furnace-supporting columns. I-beams 5 are sometimes used to back up the elements 4. Their position may correspond to that of the boiler supporting columns.

In this invention, I contemplate an arrangement of large fire brick headers arranged to form shelves at the inner side of the permanent wall, between which projecting headers, at the inside of the wall, are arranged replaceable courses of smaller fire brick as headers and stretchers. The large

headers form a part of the permanent wall, and a facing of smaller fire brick is shown as a replaceable wall.

Rows of relatively thick and long fire bricks 20 are laid as bonding elements or 70 headers upon the top of the channel irons 4. These headers 20 are laid substantially as shown in Figure 1 to project to the inner side of the wall. Each header element 20 has an opening 21 adapted to be vertically 75 disposed over an iron 4, when the header is in proper projecting, shelf-forming position. The channel iron 4 is filled with mortar as at 41, the header is then properly positioned either to rest directly upon the top of the iron, or to be slightly spaced above the iron, when the mortar on adjacent courses lies above the iron. A pin 22 is then introduced through the opening 21 and pressed into wet mortar to lock the header to the metal element against movement in longitudinal direction. In addition, each brick has corner notches 23, see Figure 6. When the bricks are laid, adjacently arranged notches 23 contact to form a groove which can be filled with mortar or "pointed" after laying. This device eliminates the need of spreading mortar on the end faces of the units during laying. The advantages of this construction are set forth in my pending application, Serial #138,455, filed September 29, 1926.

It will be noted that the reinforcing elements 4 lie at the outer side of the permanent wall, where they are more protected from the heat.

The permanent wall is now completed by superposing courses of common brick 25 laid as stretchers, the thickness of the wall thus formed being approximately the length of the common brick. As shown in Figure 1, 105 the ends of the elements 20 are exposed at the outer side of the permanent wall, while in Figure 7, the ends are covered. To cheapen the construction, the metallic elements can be spaced a greater distance apart, and I 110 have shown such condition in all the figures. When this is done, I use heavy brick header courses positioned intermediately of the courses of shelf-forming elements 20 vertically immediately between those courses.

The inner faces of the common brick 25 are protected by a wall composed of bricks 30. These bricks are formed of fire-resisting material, and the thickness of the wall is that of one brick. This wall extends vertically between the elements 20 and supports and is supported by said elements. The above mentioned construction constitutes the permanent wall, except where it is desirable to cheapen the structure in which case additional heavy headers 28 as shelf-forming elements are used. I have shown one row of such headers in Figure 1, and in Figure 7 I have shown two such rows. In each case, the permanent wall comprises the bricks 25,

30 along with the header elements 20, the latter supported upon the horizontal metallic elements 4.

In Figure 1, the ends of the bricks 28 are exposed at the outer side of the permanent wall, while in Figure 7, they are covered. This latter construction is neater.

The replaceable wall comprises in all cases firebricks 31, preferably of ordinary size, laid as headers vertically between the shelf-forming elements 20, or between elements 20 and 28 when the elements 28 are used. At that portion of the wall which received greatest heat, the firebrick headers 31 project beyond the ends of the shelf-forming headers, in this instance substantially a distance equal to one-half the length of the brick. The rear ends of the bricks 31 abut the firebrick course 30. It will be understood that the header elements 28 may be formed of a material such as common bricks are made of, or the same may be formed of fire-resisting material.

To protect the outer ends of the header elements 20 or of the elements 20, 28, I use fire brick courses 34 laid as stretchers. In this instance, two courses are used to conform to the thickness of the elements 20, 28.

The protection of the end faces of the shelf-forming headers is generally provided only at that portion of the wall which receives the greatest amount of heat, and therefore in the upper portion of the wall where the heat is not so great, certain of the shelf-forming headers 20 extend entirely through and have their inner faces exposed. In this instance, the projecting portions of the headers are longer; therefore these elements are longer. I prefer to cover the inner ends of the elements 28 at all points in the wall, inasmuch as these elements, for the sake of cheapness, may be formed from material used for common brick.

This construction is very rigid and little buckling or twisting of the wall is found to take place under the most intense and prolonged heating conditions. Any of the elements of the replaceable wall can be easily removed or replaced without dismantling the wall as a whole.

I claim as my invention:

1. A wall having a permanent portion comprising a plurality of superposed channel irons extending lengthwise of the wall, rows of fire bricks laid upon the tops of the irons as headers and projecting at the inner side of the wall to form shelves, bricks filling the space between the headers and irons beneath and above the same, including only 60 stretcher courses at the outer portion, and a replaceable portion comprising bricks laid as headers and supported between the shelf-forming headers and abutting the stretcher courses.

2. A wall comprising a plurality of su-

perposed irons extending lengthwise of the wall and topped with mortar, rows of fire bricks laid upon the irons as headers and projecting at the inner side of the wall to form shelves, each brick having a pin passing therethrough and into the mortar, bricks filling the space between the headers and irons beneath and above the same, and a replaceable wall portion comprising bricks laid as headers and supported between the shelf-forming headers.

3. A wall comprising a plurality of superposed irons extending longitudinally thereof at the outer side, rows of fire bricks laid as headers upon the iron and projecting beyond the wall at the inner side, bricks filling the space between the irons and fire bricks, including courses laid as stretchers, and a replaceable wall comprising fire bricks laid as headers and supported between the first mentioned headers, and courses laid as stretchers and supported by the last mentioned headers to cover the ends of said metal-supported headers.

4. A wall comprising a plurality of superposed channel irons extending lengthwise of the wall, rows of relatively thick and long fire bricks laid upon the irons as headers and projecting at the inner side of the wall and forming shelves, bricks filling the space above and beneath the irons and headers thereon, including courses laid as stretchers, a single course of brick laid as stretchers against the first mentioned stretcher courses, as a facing for the inner faces of said courses and said irons, and fire bricks laid as headers and supported between the shelf-forming headers and abutting the last facing stretcher courses, and additional rows of fire brick laid as stretchers and covering the inner ends of the shelf-forming headers.

5. A wall comprising a plurality of superposed channel irons extending lengthwise of the wall with their concave faces directed upwardly and containing mortar, rows of fire bricks laid upon each iron as headers and projecting at one side of the wall to form shelves, each brick having a pin passing therethrough and into the mortar, bricks filling the space between the irons and shelf-forming fire bricks, including courses laid as stretchers, and fire bricks laid as headers and supported between the shelf-forming headers and abutting the stretcher courses.

6. A wall comprising a plurality of superposed channel irons extending lengthwise of the wall and containing mortar, rows of fire bricks laid upon the irons as headers and projecting at the inner side of the wall to form shelves, each brick having a pin passing therethrough and into the mortar, bricks filling the space between the headers and irons beneath and above the same, including courses laid as stretchers, and a re-

- placeable wall portion comprising bricks laid as headers and supported between the shelf-forming headers and abutting the stretcher courses.
5. 7. A wall comprising a plurality of superposed irons extending longitudinally thereof at the outer side, rows of large fire bricks laid as headers upon the iron and projecting beyond the wall at the inner side, bricks filling the space between the irons and fire bricks, including large intermediately disposed bricks laid as headers, and a replaceable wall comprising fire bricks laid as headers and supported between the large headers, and courses laid as stretchers and supported by the last mentioned headers to cover the ends of said large headers.
8. A wall comprising a plurality of superposed channel irons extending lengthwise of the wall, rows of relatively thick and long fire bricks laid upon the irons as headers and projecting at the inner side of the wall and forming shelves, bricks filling the space above and beneath the irons and headers thereon, including additional thick and long fire brick courses laid as headers, a single course of brick laid as stretchers between long headers against the first mentioned stretcher courses, as a facing for the inner faces of said courses and said irons, and fire bricks laid as headers and supported between the long shelf-forming headers, and abutting the last facing stretcher courses, and additional rows of fire brick laid as stretchers and covering the inner ends of the shelf-forming headers.
9. A wall comprising a plurality of superposed channel irons extending lengthwise of the wall with their concave faces directed upwardly and containing mortar, and rows of fire bricks laid upon each iron as headers and projecting at one side of the wall to form shelves, each brick having a pin passing therethrough and into the mortar.
45. 10. A bonding brick having an opening extending therethrough adjacent one end arranged to be vertically disposed when the brick is laid.
11. A wall having a permanent portion comprising corner angle irons and a plurality of superposed channel irons extending lengthwise between the corner irons and attached thereto, rows of fire bricks laid upon the irons as headers and projecting at the inner side of the wall to form shelves, bricks filling the space between the headers and irons, and laid as stretchers, and a replaceable wall comprising bricks laid as headers, supported between shelf-forming headers and abutting stretcher courses.
12. A wall comprising corner posts as angle irons, a plurality of superposed channel irons extending lengthwise of the wall and adjustably connecting with the corner posts said irons having their concave faces directed upwardly and containing mortar, rows of fire bricks laid upon each iron as headers and projecting at one side of the wall to form shelves each brick having a pin passing therethrough and into the mortar, bricks filling the space between the irons and shelf forming fire-brick, including courses laid as stretchers and fire bricks laid as headers and supported between the shelf forming headers and abutting the stretcher courses.
13. A wall comprising corner posts as angle irons, a plurality of superposed channel irons extending lengthwise of the wall and connecting with the corner posts said irons having their concave faces directed upwardly and containing mortar, and rows of fire bricks laid upon each iron as headers and projecting at one side of the wall to form shelves, each brick having a pin passing therethrough and into the mortar, and bricks filling the spaces between the headers, at the inner side of the wall.
14. A wall having a permanent portion comprising corner posts connected by single length superposed irons as tie and stiffening elements, extending lengthwise between the posts, rows of fire bricks laid upon the irons as headers and projecting at the inner side of the wall to form shelves, bricks filling the space between headers and irons beneath and above the same.
15. A wall having a permanent portion comprising corner posts connected by single length superposed irons as tie and stiffening elements, extending lengthwise between the posts, rows of fire bricks laid upon the irons as headers and projecting at the inner side of the wall to form shelves, bricks filling the space between headers and irons beneath and above the same, including stretcher courses, some of which assist in protecting the inner faces of the irons, and a replaceable wall comprising bricks laid as headers, and abutting the stretcher courses.
16. A wall having a permanent portion comprising corner posts connected by single length superposed channel irons as tie and stiffening elements, extending lengthwise between the posts, rows of fire bricks laid upon the irons as headers and projecting at the inner side of the wall to form shelves, bricks filling the space between headers and irons beneath and above the same, including courses laid as stretchers at the outer side of the wall and a replaceable portion comprising bricks laid as headers and supported between the shelf-forming headers, and abutting the stretcher courses.

In witness whereof, I have hereunto set my hand this 7th day of October, 1926.

MICHAEL LIPTAK.
